DESIGN FOR A JEWELRY PIN

Arthur Brand, New York, N. Y.

Application August 26, 1944, Serial No. 115,049

Term of patent 7 years

(Cl. D45—19)

To all whom it may concern:

Be it known that I, Arthur Brand, a citizen of the United States and resident of New York, in the county and State of New York, have invented a new, original, and ornamental Design for Jewelry Pin, of which the following is a specification, reference being had to the accompanying drawing, forming part thereof, in which:

Fig. 1 is a front elevational view of a jewelry pin showing my new design, and

Fig. 2 is a top edge view thereof.

I claim:

The ornamental design for a jewelry pin, as shown.

ARTHUR BRAND.
